UNITED STATES PATENT OFFICE.

FRANCISCO V. DE BEM, OF GLOUCESTER, MASSACHUSETTS.

REEFING APPARATUS FOR FORE-AND-AFT SAILS.

SPECIFICATION forming part of Letters Patent No. 569,602, dated October 20, 1896.

Application filed June 12, 1896. Serial No. 595,280. (No model.)

To all whom it may concern.

Be it known that I, FRANCISCO V. DE BEM, a subject of the King of Portugal, residing in Gloucester, in the county of Essex and State 5 of Massachusetts, have invented a new and Improved Reefing Apparatus for Fore-and-Aft Sails, of which the following is a specification.

This is an improved apparatus for reefing 10 mainsails and foresails in schooner and sloop rigged vessels; and it has for its object to enable the reefing process to be accomplished quickly and at the upper corner or peak of the sail, that is to say, that portion near the 15 peak of the gaff. This portion of the sail is, of course, that which places the boat in the greatest danger in case of a sudden squall or blow, and my reefing apparatus takes in sail at that point by dropping instantly the peak 20 of the gaff, thus practically converting the sail into a leg-of-mutton sail.

The nature of the invention is fully described below, and illustrated in the accompanying drawings, in which—

25 Figure 1 is a side elevation of a portion of a vessel provided with my reefing apparatus and with the mainsail raised to its full extent. Fig. 2 is a similar view with a reef taken in the mainsail. Fig. 3 is an enlarged vertical 30 section taken through the gaff-jaws or gaff-yoke and showing a portion of the mast and gaff in elevation. Fig. 4 is a horizontal section taken through the gaff-yoke and the mast.

Similar letters of reference indicate corresponding parts.

35 A represents the mast, B the mainsail, and C the gaff. The gaff is enabled to swing vertically from the gaff-yoke by means of the horizontal pivot D, which is secured to the 40 horizontal extensions E' of the jaw E, said jaw being on the forward side of the mast and made slightly convex in vertical section in order to facilitate its sliding up and down as the sail is raised and lowered. The other jaw 45 F is provided with the inner extensions F', through which the pivot D extends, and said jaw F is also made convex in vertical section for the same purpose as the jaw E. From the pivot D a bail D' extends upward, and 50 from this bail the halyard or rope H extends

over a block e to the deck as usual for raising the mainsail.

A rope K is secured at K' to the peak of the mainsail a short distance below the peak of the gaff, extends up over a pulley a on one 55 side of the gaff, and thence down over a block b, secured to one side of one of the rings or hooks d, which secure the mainsail to the mast, and thence the rope K extends down to the deck, to which it may be secured in any 60 desired manner. Another of these ropes is secured to the opposite side of the mainsail at the point K' and passes over a pulley a and block b on the opposite sides of the gaff and mast. L represents the peak-halyards, 65 extending from the peak to the mast and thence to the deck in the ordinary manner.

To reef the mainsail, let go the peak-halyard L and the sail will swing down from the pivot D on the leeward side into the position 70 indicated in Fig. 2. Then draw the gaff close to the mast and take up the slack in the sail by clewing down the rope K on the leeward side and securing it at g, and make taut the rope K on the windward side by securing it 75 at h. Thus the reefing process is accomplished almost instantaneously, and the sail is reefed at the point where the wind has the greatest leverage, viz., at the peak.

This reefing apparatus may be applied to 80 sails of this type on sloops, schooners, and any other vessels employing fore-and-aft sails.

Having thus fully described my invention, what I claim, and desire to secure by Letters Patent, is—

85 In a reefing apparatus of the character described, in combination, the mast; the gaff-yoke consisting of the jaws E and F provided respectively with the extensions E' and F'; the gaff pivoted to said extensions so as to 90 swing vertically therein; the sail B; peak-halyard; and the ropes K secured at K' to opposite sides of the sail and extending therefrom over suitable pulleys on the gaff and suitable blocks on one of the rings or hooks 95 d to the deck, substantially as described.

FRANCISCO V. DE BEM.

Witnesses:

HENRY W. WILLIAMS,
A. N. BONNEY.
